UNITED STATES PATENT OFFICE.

CHARLES DOEHRING, OF NEW YORK, N. Y.

ELECTRIC BATHING APPARATUS.

SPECIFICATION forming part of Letters Patent No. 533,791, dated February 5, 1895.

Application filed June 22, 1894. Serial No. 515,363. (No model.)

To all whom it may concern:

Be it known that I, CHARLES DOEHRING, of New York, N. Y., have invented an Improved Electric Bathing Apparatus, of which the following is a specification.

This invention relates to an electric bathing apparatus by which the bather is subjected to the joint action of metallo therapeutics and a dry bathing medium.

10 In the accompanying drawings, Figure 1 is a perspective view of my improved bathing apparatus. Fig. 2 is a vertical longitudinal section of a modification. Fig. 3 is a plan of Fig. 2; Fig. 4, a cross section on line 3, 3, Fig. 15 3, and Fig. 5 a detail of portions of the flexible metal sheets *d* and *e*.

20 My improved apparatus consists essentially of two flexible metal sheets between which an electric current is generated and of a bed of 20 heated sand in which the bather is packed while subjected to the electric action between the sheets.

25 In Fig. 1, *d* and *e* are the upper and lower flexible metallic sheets, of which one constitutes in effect a mattress and the other a cover. The lower sheet *e* I prefer to construct of textile fabric with interwoven metal strands, while the upper sheet *d* is preferably composed of linked wire or wire netting. Between the sheets *d*, *e*, electric action is maintained either by constructing one sheet of zinc and the other of copper and connecting them at one end by a wire *f*, or by connecting both sheets to a battery or other source 35 of electricity by the line wires *f'*.

30 The sheets *d*, *e*, are used in connection with bedding *c* of heated sand, which packs around the bather and the sheets. This sand will cause the bather to perspire freely and the 40 moisture thus obtained will intensify the electric action between the sheets *d*, *e*. In this way a continuous therapeutic action is maintained, which has hitherto not been practicable, and highly beneficial results for the 45 bather will be produced.

45 In Figs. 2 to 5, the invention is shown to be applied to a bathtub *a*, in which hot air or sand may be used as the bathing medium. Here the bath tub is provided with a false 50 bottom *a'*, so as to produce a hot air or steam jacket *a*. The tub is lined with wooden slats *b*, to prevent accidental contact between the bather and the heated tub. Into the jacket *a* leads a pipe *a* adapted for the introduction of hot air or steam, while a second pipe 55

a, leads directly into the body of the tub. The pipe *a*, is provided with two laterally extending outlets, that discharge if desired, steam, water or hot air into the body of sand *c* with which the tub may be completely or 60 partially filled. Within the tub *a* are suspended the flexible metallic sheets *d* and *e*, constructed as previously described, between which the electric action is maintained and connected if desired to a battery *h*. The 65 sheets *d* and *e*, are suspended from the head and foot board of the bath tub by means of hooks *g*, as shown.

In use the jacket *a* is filled with hot air or steam, while the tub itself may be filled with 70 sand. The heated jacket will keep the sand at such a high temperature as is necessary to produce the desired effect upon the bather. If the sand is omitted, the perspiration of the 75 bather is effected by the air within the tub heated by the jacket *a*.

The sand may be admixed with shot, salt or other electric conductor, to strengthen the electric action between the metal sheets.

By my apparatus, I am enabled to subject 80 the entire surface of the body to electric action by a simultaneous application of metallo-therapeutics and arenation and thus treatments in which external moistening of any part of the human body must be avoided, may 85 be readily effected.

What I claim is—

1. A bathing apparatus composed of two flexible metal sheets adapted to form a support and a covering for the bather, and between which an electric current is adapted to be generated, substantially as specified.

2. A bathing apparatus composed of two flexible metal sheets constituting electrodes and of an interposed dry packing, substantially as specified.

3. A bathing apparatus composed of a tub having a heating jacket and of a pair of flexible metal sheets suspended therein and constituting electrodes, substantially as specified.

4. An electric bath composed of a flexible metallic support, a flexible covering, constituting either electrodes or electric generators, and a dry bathing medium, substantially as specified.

CHARLES DOEHRING.
